UNITED STATES PATENT OFFICE.

EMANUEL A. SPEEGLE, OF LOS ANGELES, CALIFORNIA.

COMBINATION EXCAVATOR AND DREDGE.

Application filed April 16, 1926. Serial No. 102,423.

My invention relates to a combination machine or apparatus that embodies the principles of an excavator, dredge, and material handling and dumping mechanism, and the 5 principal objects of my invention are to generally improve upon and simplify the construction of the existing forms of similar machines; to provide a combined excavating and dredging machine that may be drawn or 10 moved forward and actuated by a motor truck, street car, or locomotive; further, to provide a machine with cutters that are arranged to enter the ground and loosen the same in order that the loose material may be 15 readily engaged by a traveling carrier or conveyor and moved upwardly through the machine to the point of discharge on a transversely disposed carrier; and further, to provide simple means whereby the machine 20 may be vibrated in order to move the cutters into and through the ground or material that is being acted upon by the apparatus.

A machine embodying the principles of 25 my invention may be advantageously employed in dredging and excavating operations for the construction of shallow drains and irrigation ditches, for the removal of snow and ice from roadways, and for performing various other operations where the 30 rapid and economical handling of large quantities of earth, gravel, or other materials, is desired.

With the foregoing and other objects in 35 view, my invention consists in certain novel features of construction and arrangement of parts that will hereinafter be more fully described and claimed and illustrated in the accompanying drawings, in which—

40 Fig. 1 is a side elevational view of a combined excavating and dredging machine of my improved construction.

Fig. 2 is a front elevational view of the 45 machine.

Fig. 3 is a rear elevational view of the machine with the endless conveyor removed.

Fig. 4 is a plan view of a portion of the 50 endless conveyor used in my improved machine.

55 Referring by numerals to the accompanying drawings, 10, 10' designate the side members of a skeleton frame that is made up of angle irons or channels suitably braced, and said frame is supported in an inclined position on an axle 11, the latter being provided with suitable wheels 12. Journaled in

bearings 13 that are located on the intermediate portion of the frame is a transversely disposed shaft 14, and loosely journaled on the ends of said shaft are the ends of links or draw bars 15, the outer ends of which are adapted to be connected to the frame of a motor truck, tractor, street car, or the like.

As illustrated in Fig. 1 the draw bars 15 are extended forwardly from the frame of the machine so that the latter will be drawn forwardly by the forwardly moving truck or tractor, but in the event that the machine is to be pushed forwardly in front of the truck or tractor, then the draw bars 15 are arranged so that they project rearwardly of the machine as illustrated by dotted lines in Fig. 1.

Supported upon the axle 11 and by hangers 16 that depend from the intermediate portions of the frames 10 is an inclined tube or housing 17 that is preferably rectangular in cross section, both ends of said housing being open and the lower end terminating in a plane just above the surface of the ground over which the machine passes.

Journaled in bearings 18 at the upper forward end of the frame of the machine is a shaft 19 to which is fixed a pair of large sprocket wheels 20, and journaled in bearings 21 on the underside of the frame of the machine and just above the lower open end of the tubular housing 17 is a shaft 22 which carries a pair of sprocket wheels 23 that are similar to the sprocket wheels 20. Journaled in adjustable bearings 24 that are arranged on the lower rear portion of the skeleton frame is a shaft 25 carrying a pair of sprocket wheels 26 that are similar to the wheels 20 and 23, and supported by and passing around the pairs of sprocket wheels 20, 23, and 26 is the endless carrier or conveyor of my improved machine.

This conveyor is made up of a pair of side chains and each side chain comprises a series of oval links 27 that are connected by pairs of strip links 28. The oval links 27 are adapted to enter the notches in the peripheries of the sprocket wheels 20, 23, and 26, and the under-running portions of both chains pass upwardly through the tubular housing 17 in their travel from the sprocket wheels 23 to the sprocket wheels 20.

Formed integral with the inner faces of the links 27 are vertically disposed ribs 27a to which are riveted or bolted the ends of transversely disposed plates 29 that function

as scrapers to carry the material upwardly through housing 17 and formed on the outer edges of these plates 29 are short outwardly projecting fingers 29^a that are adapted to dig 5 or bite into the loose material as the same is engaged and lifted by said plates and carried into and through the housing or chute 17. For the accommodation of these fingers 29^a, the bottom of the housing 17 is provided 10 with longitudinally disposed grooves or channels 17^a through which the fingers travel as the plates 29 move upwardly through the chute.

Any slack that occurs in the endless conveyor 15 may be taken up by adjustment of the bearings 24 that carry shaft 25.

Shaft 14 is positively driven from the motor truck or tractor by a sprocket chain 30 that passes around a sprocket wheel 31, the 20 latter being fixed on said shaft 14 and the endless conveyor is driven from shaft 14 by means of a sprocket chain 32 that passes around a sprocket wheel 33, which latter is fixed on shaft 14, said sprocket chain also 25 passing around a sprocket wheel 34 that is fixed on shaft 19 (see Fig. 3.)

Carried by the rear portion of the frame of the truck or tractor that is used for drawing my improved excavating apparatus is a 30 frame 35 that is disposed transversely beneath the forward portion of the frame 10 and arranged for operation within the bottom of this transversely disposed frame is an endless carrier 36 that operates on rollers 37, 35 the latter being arranged at the ends of the frame. One of the rollers 37 is provided at its end with a sprocket wheel 38, and passing around the latter is a sprocket chain 39 that extends upwardly around the sprocket 40 wheel 40. This sprocket wheel is carried on a shaft 41 that is journaled in suitable bearings at the upper end of the main frame 10 of the excavator and said shaft being connected by meshing beveled pinions 42 with 45 shaft 19.

The parts just described provide means for imparting movement to the endless belt or conveyor 36 that operates in the lower portion of frame 35 and this frame is arranged 50 so that it receives the material that discharges from the upper end of the chute or housing 17. Frame 35 and endless conveyor 36 extend a suitable distance away from one side of the machine and thus the material that is excavated and elevated by my improved machine is discharged into a suitable receptacle or onto the ground to one side 55 of the path of travel of the apparatus.

Fixed to and depending from the under- 60 side of chute 17 and slightly to the rear of axle 11 is a series of cutting blades or colters 43 that are adapted to enter and pass through the ground or soil a short distance in front of the open lower end of chute 17. 65 Depending from the rear portion of the

frame 10 and between shafts 22 and 25 are brackets 44, and arranged between the lower ends thereof is a transversely disposed scraper 45.

Depending from the sides of frame 10 between the shafts 22 and 25 are supports 46 to the lower ends of which are secured elongated colters or cutting blades 47 that occupy inclined positions and the forward portions of these blades are curved upward and secured to the sides of chute 17 at the lower end thereof. Likewise the rear ends of these blades are curved upward. These side colters 47 are designed to enter the ground at the sides of the channel formed by the colters 43 and scraper 45, thus defining the sides of the channel that is cut by the machine while in operation.

In some instances it may be found desirable to vibrate the machine vertically or to rock the same upon the axis provided by the axle 11 and which vibratory action materially increases the effectiveness of the colters in passing into and through the ground or material that is being acted upon, and in order to bring about this vibratory movement a transversely disposed shaft 48 is journaled in the draw bars 15 and secured on said shaft is a sprocket wheel 49 and a disk 50, which latter is provided with a 90 series of apertures 51.

Pivots connected to disk 50 is the lower end of a link 52, the upper portion thereof carrying a pair of bolts 53 that are adapted to pass through a slot 54 that is formed in an upwardly projecting link 55, the upper end of the latter being pivotally connected to the upper portion of the frame 10 of the machine.

Sprocket wheel 49 receives a sprocket chain 56 that is driven from a sprocket wheel mounted on the tractor that is used in operating the excavator and as this sprocket chain is operated, rotary motion will be imparted to shaft 48 and, as disk 50 is rotated, the connected links 52 and 55 will be reciprocated vertically, thereby imparting vertical vibratory or swinging movement to the frame of the excavator. The axis of this swinging movement is the axle 14 and as the lower portion of the machine vibrates vertically, the colters 43 and 47 will move through vertical arcs, thereby tending to cause said colters to move more readily through the material and such action will tend to cut weeds, vines, small brush, and the like, that may be encountered during the travel of the excavator.

The degree of vibratory movement may be controlled by adjusting the links 52 and 55 upon each other, which adjustment is effected by the slot and bolt connections between said links, and when it is desired to operate the machine without imparting vibratory movement thereto, sprocket chain 125

56 is disconnected from sprocket wheel 49 and disk 50 is locked to one of the draw bars 15 by the insertion of a bolt 57 through an aperture in the draw bar and through 5 one of the apertures 51. Inasmuch as there is a series of these apertures 51, the angular position of the excavator relative to a horizontal plane may be adjusted for a limited distance.

10 In the operation of my improved excavator the machine is moved forward by a tractor or the like, and the colters 43 passing through the ground, thereby loosening the same so that it may be readily picked 15 up by the transverse blades 29 of the conveyor as the latter passes beneath sprocket wheels 23 which are positioned directly behind the lower end of chute 17 and above the scraper 45. The loose material is engaged by the transverse members 29 of the conveyor and carried upwardly through 20 chute 17 and discharged onto the apron or conveyor 36 in frame 35 and said material is carried to the side of the machine and 25 discharged in a row that parallels the path of travel of the machine, or the excavated material may be discharged into a suitable receptacle.

The endless conveyor is driven from the 30 tractor through sprocket chain 30, sprocket wheel 31, shaft 14, sprocket wheel 33, sprocket chain 32, sprocket wheel 34, and shaft 19, that carries the sprocket wheels 20 at the upper end of the machine, and the endless belt or apron 36 in frame 35 is 35 driven from shaft 19 through the beveled pinions 42, sprocket chain 39 and sprocket wheel 38 that is arranged on the rear one of the rollers 37.

40 An excavator of my improved construction is comparatively simple, and may be advantageously employed for all excavating purposes, for the construction of ditches and drainage channels in sub-irrigation projects, for the removal of snow and ice from roadways, and for dredging mud, gravel and water in mining operations.

45 Further, by elongating the apparatus, and particularly the chute or housing 17, the apparatus may be used to advantage in ele-

vating water from one level to another, and which operation is frequently employed in irrigation and mining operations.

It is to be understood that my invention in its particular construction may be used 55 for any desired purpose and that changes, variations, and modifications may be made in the size, form, and construction of the various parts of the apparatus as will fall within the scope of the appended claims. 60

I claim as my invention:

1. In an excavator a pair of horizontally disposed draw bars that are adapted to be connected to a tractor, a shaft supported by said draw bars, a wheel-supported frame 65 mounted for rocking movement on said shaft, an endless conveyor arranged for operation on said frame and a chute carried by said frame and arranged to be traversed by the under-running portion of said conveyor. 70

2. In an excavator of the class described a pair of horizontally disposed draw bars that are adapted to be connected to a tractor, a shaft supported by said draw bars, a 75 wheel-supported frame mounted on said shaft, an open-ended inclined chute arranged beneath said frame, an endless conveyor mounted for operation on said frame with its under-running portion passing through said chute, colters depending from the underside of said chute and a scraper arranged beneath said frame to the rear of the lower open end of said chute. 80

3. In an excavator of the class described a pair of horizontally disposed draw bars that are adapted to be connected to a tractor, a shaft supported by said draw bars, a wheel-supported frame mounted on said shaft, an open-ended inclined chute arranged beneath said frame, an endless conveyor mounted for operation on said frame with its under-running portion passing through said chute, colters depending from the underside of said chute, a scraper arranged beneath said frame to the rear of the lower open end of said chute and colters arranged to the sides of said scraper. 85 90 95

In testimony whereof I affix my signature.

EMANUEL A. SPEEGLE.
